MEANS FOR AND METHOD OF PREVENTING
LOCOMOTIVE WHEEL SLIPPAGE

Harry A. Hoke, Altoona, and Norman E. Merrell,
Norwood, Pa., assignors to The Pennsylvania
Railroad Company, Philadelphia, Pa., a corpora-
tion of Pennsylvania

Application February 11, 1943, Serial No. 475,508

8 Claims. (Cl. 105—48)

This invention relates to means for preventing slippage of locomotive wheels, particularly in starting with heavy loads, and also to methods of accomplishing this result.

More specifically, the present invention is concerned with steam locomotives of the type having four cylinders for motivating the driving wheels.

In the operation of locomotives of the kind referred to, violent slippage of one or the other set of the driving wheels often occurs by reason of their having, at times, a lesser co-efficiency of friction with the track rails than the remaining set, so that ordinarily all of the steam ahead of the control throttle and in the connecting piping will pass to the cylinders of such slipping wheel sets. During disturbances of this sort, the engineman has no control whatever over the supply of steam which has passed the control throttle, and as a result, the locomotive will frequently come to a standstill before the steam has passed out of the piping.

Our invention has for its chief object to overcome the difficulties above pointed out, that is to say, to make it possible to slow down those drivers of the set which may tend to slip without interfering with the functioning of the other set, until the wheels of the slipping set take hold. This objective is attained in practice as herein-after more fully disclosed, through provision of automatic means in the form of a valve which is sensitive to differential steam flow in pipes leading to the four cylinders of the locomotive for capacity to temporarily reduce the supply of steam to the motivating cylinders of the slipping wheels, while allowing full supply of steam to the other pair of cylinders.

Other objects and attendant advantages of our invention will appear from the following detailed description of the attached drawings, whereof

Fig. 1 is a broken out fragmentary view, more or less diagrammatic, partly in side elevation and partly in longitudinal section, of a steam locomotive conveniently embodying the present improvement.

Fig. 2 is a cross sectional view of the locomotive taken as indicated by the angled arrows II—II in Fig. 1.

Fig. 3 is a view drawn to a larger scale and showing, partly in side elevation and partly in longitudinal section, the automatic valve means for preventing wheel slippage in accordance with our invention.

Figs. 4 and 5 are detail sectional views taken as

respectively indicated by the angled arrows IV—IV and V—V in Fig. 3.

The locomotive illustrated in Fig. 1 for the purposes of exemplification herein is of the four cylinder type and generally of standard construction having a boiler 1, and two pairs of cylinders 2 and 3 with piston rod and pitman connections at each side thereof for motivating corresponding sets of driving wheels 4 and 5 in the usual way. At 6 is partially indicated the dry steam pipe which leads from the steam dome 7 of the boiler to the header 8 of the superheater in the smoke box 9 at the front end of the locomotive, with which header is incorporated a control 10 throttle valve 10 of suitable approved design. Extending downward from the housing of the throttle valve 10 at each side of the boiler is a manifold pipe 11, see Figs. 1 and 2, with axially-aligned horizontal branch pipes 12 and 13 leading in opposite directions therefrom to the front and rear cylinders 2 and 3 respectively.

The wheel slippage prevention means with which our invention is more especially concerned is indicated comprehensively in the drawings by the numeral 15, and, as shown, is in the form of a valve with a body 16 of T configuration to serve as a juncture fitting between the manifold pipe 11 and its horizontal branches 12 and 13. The axially aligned end portions 17 and 18 (Fig. 3) of the valve body 16 are provided with apertured flanges 19 and 20 for connection to similar opposing flanges 21 and 22 at the corresponding ends of the branch pipes 12 and 13 by means of screw bolts 23 and 24. The upward neck 25 of the valve body 16 is likewise provided with an apertured flange 26 for connection to the shell of the boiler 1 and to a flange 27 at the lower end of the manifold pipe 11 by means of screw bolts 28. Bearings 29 and 30 supported within the reduced end portions 17 and 18 axially within the valve body 16 by radial spider webs 31 and 32, constitute guides for the ends of a slide rod, which is composed of two halves or sections 33 and 34. As shown the rod sections 33 and 34 are reversely threaded at their inner ends and joined by a turn buckle 35, relative rotation of said sections being precluded by jam nuts 36. Mounted on the rod sections 33 and 34 are discous closure members 37 and 38 respectively, which are adapted to coact with ports 39 and 40 adjacent opposite ends of the valve body 16 in controlling flow to the corresponding cylinders 2 and 3 as presently explained. The closure members 37 and 38 are cupped centrally as at 37a, 38a to receive the contiguous ends of coiled helical com-

pression springs 41 and 42 which respectively surround the rod sections 33 and 34 and which react upon flanged sleeves 43, 44 and 45, 46 free on said sections 33 and 34. As further shown, these sleeves 43, 44 and 45, 46 respectively abut the bearings 29 and 30, and the bottoms of the cup portions 37a and 38a of the closure members 37 and 38 which latter are welded fast to the respective rod sections 33 and 34 against integral polygonal collars 47 and 48 on said sections. The springs 41 and 42 are identical both as to size and power, and are regulatable through endwise adjustment of said rod sections 33 and 34 in relation to each other by means of the turn buckle 35. The turn buckle 35 is accessible for the purpose of adjustment, through a hand hole 50 in the valve body 16 near the bottom of the latter. This hand hole 50 is normally closed by a removable cover disc 51 having an axial stem 52 which passes outwardly through an apertured clamp yoke 53 and is provided with a securing nut 54 at its protruding threaded end.

Preferably the body 16 of the valve 15 is formed from wrought parts which are integrally united by weld joints as conventionally indicated. However, if desired or found more convenient in practice, it may be constructed as a casting.

The operation of our invention is as follows: Ordinarily, the slide rod with its closure discs 37 and 38 occupies the central neutral position in which it is shown in Fig. 3, with steam flowing uniformly through the branch pipes 12 and 13 to the cylinders 2 and 3. In the event that one set of driving wheels, for example the front set 4, should tend to slip due to decreased friction with the track rails, there will be an accelerated flow of steam through the branch pipe 12 whereby the slide rod will be drawn forwardly (rightward) and the spring 41 compressed with attendant approach of the closure member 37 toward the port 39 to reduce the supply of steam to the cylinder 2 until the slipping driving wheels again take hold. It will be understood, of course, that during this action the cylinder 3 will receive its usual supply of steam and function in the normal way to motivate the drivers 5. When the frictional resistivity of the slipping wheels is re-established, the rod and its closure member 37 will be automatically returned to the neutral illustrated position by the spring 41, in a way readily understood from Fig. 3. Similarly, slippage of the rear set of driving wheels 5 will be attended by shifting of the rod to the left and compression of the spring 42, with resultant approach of the closure member 38 toward the port 40 to reduce the supply of steam to the cylinder 3 until said wheels again take hold, whereupon the parts will again be returned to neutral position by said spring 42.

Having thus described our invention, we claim:

1. In a steam locomotive, a boiler; a plurality of cylinders for motivating separate driving wheels; conduits for conducting steam from the boiler to the respective cylinders; and control means in said conduits directly responsive to differential velocity flow of steam in said conduits upon slippage of any of the driving wheels, to automatically reduce the supply of steam to the corresponding cylinders until such slipping wheels take hold.
2. In a steam locomotive, a boiler; a plurality of cylinders for motivating separate driving wheels; conduits for conducting steam from the boiler to the respective cylinders; and a control valve with movable closure means in said con-

duits directly responsive to differential velocity flow of steam in said conduits upon slippage of any of the driving wheels, to automatically reduce the supply of steam to the corresponding cylinders until such slipping wheels take hold.

3. In a steam locomotive, a boiler; a plurality of cylinders for motivating separate driving wheels; a manifold with branch conduits through which steam is conducted to the individual cylinders; and a control valve interposed at the juncture of the manifold and its branches, said valve having movable closure means directly responsive to differential velocity flow of the steam in said branches upon slippage of any of the driving wheels, to reduce the supply of steam to the corresponding cylinders until such wheels take hold.

4. The invention according to claim 3, wherein the branch pipes are aligned; and wherein the valve has a body in the form of a T fitting which connects the manifold pipe with the branch pipes, which has ports for communication into the branch pipes, and which houses closure means sensitive to differential flow of steam in said branch pipes to close the port for the cylinders of the slipping wheels.

5. The invention according to claim 3, wherein the branch pipes are horizontally aligned; and wherein the valve has a body in the form of a T fitting which connects the manifold pipe with the branch pipes, which body has ports for communication into the branch pipes, and which houses closure means sensitive to differential flow of steam in said branch pipes to close the port for the cylinders of the slipping wheels, said closure means including a slide rod guided at its ends in bearings coaxial with the aligned branch pipes, spaced closure members on the intermediate portion of said rod adapted to coact respectively with the ports in said body, and yielding means to normally maintain the rod and its closure members in neutral position within the valve body.

6. The invention according to claim 3, wherein the branch pipes are aligned; and wherein the valve has a body in the form of a T fitting which connects the manifold pipe with the branch pipes, which has ports for communication into the branch pipes, and which houses closure means sensitive to differential flow of steam in the branch pipes to close the port for the cylinders of the slipping wheels, said closure means including a slide rod with its ends guided in bearings within the valve body axially of the aligned branch pipes, spaced closure members on the intermediate portion of said rod adapted to coact respectively with the ports in said body, and balanced spring means in compression between the bearings and the respective closure members tending to normally maintain the rod and its closure members yieldingly in neutral position within the valve body.

7. The invention according to claim 3, wherein the branch pipes are aligned; and wherein the valve has a body in the form of a T fitting which connects the manifold pipe with the branch pipes, which has ports for communication into the branch pipes, and which houses closure means sensitive to differential flow of steam in the branch pipes to close the port for the cylinders of the slipping wheels, said closure means including a slide rod with separate end sections adjustably connected by a turn buckle and respectively guided in spaced bearings within the valve body axially of the aligned branch pipes, closure

members on said rod sections adapted to coact respectively with the ports in said body, and spring means in compression between the bearings and the respective closure members tending to normally maintain the rod and its closure members 5 yieldingly in neutral position within the valve body.

8. The method of operating a steam locomotive having plural cylinders for respectively imparting movement to individual sets of driving wheels, 10

which comprises supplying steam to all the cylinders; and apportioning the steam directly in accordance with velocity differential in the flow of steam to the respective cylinders so that less steam is furnished to the cylinders of a slipping wheel than to the cylinders of the other wheels.
